Primary Examiner — Marie D. Fast Horse*(74) Attorney, Agent, or Firm* — Schmeiser, Olsen & Watts, LLP(57) **CLAIM**

I claim the ornamental design for a video capture device, as shown and described.

DESCRIPTION

FIG. 1 is perspective view of a video capture device showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the video capture device that form no part of the claimed design.
